UNITED STATES PATENT OFFICE.

JOSEPH D. HARRIS, OF DETROIT, MICHIGAN, ASSIGNOR TO MCCORD RADIATOR & MFG. CO., OF DETROIT, MICHIGAN, A CORPORATION OF MAINE.

RADIATOR CORE.

Application filed June 27, 1925. Serial No. 40,110.

One object of my invention is to provide a core with flat spacer or division plates having truss-like projections struck out therefrom and having inclined end portions to extend into the corrugations of one of the corrugated plates between which the spacer plates are located for centering the spacer plates in assembling the core.

A further object of my invention is to have these projections hold the spacer plates against the corrugated plates on the sides opposite the projections so as to have surface contact for the transfer of heat from one plate to the other.

15 A still further object of my invention is to dispose the projections edgewise in the air passages to split or divide the air currents passing through the core to increase the air turbulence and thus turn the colder air against the heated metal to effect better cooling.

The invention consists further in the matters hereinafter described and claimed.

In the drawings—

Fig. 1 is a front elevational view of a radiator having a core embodying the features of my invention;

25 Fig. 2 is an enlarged fragmentary front elevational view of a detail of the core structure to be hereinafter described;

30 Fig. 3 is a transverse sectional view taken on line 3—3 of Fig. 2;

Fig. 4 is a view of a spacer plate of my invention and looking at the same from one side;

35 Fig. 5 is a longitudinal sectional view taken on line 5—5 of Fig. 3 with the outermost plates of the water passages and spacing strips omitted for the sake of illustration; and

40 Fig. 6 is an elevational view of a detail of construction to be hereinafter described.

The radiator, as indicated in Fig. 1, has an outer casing or shell 1 containing a core 2 embodying the features of my invention. The core is of the cellular type and has upper and lower water tanks (not shown) and a plurality of pairs of corrugated sheet metal plates 3, 4 extending vertically between the tanks and so made and arranged to form zigzag water passages 5, 5 alternated by air passages 6, 6, as in structures of this general character.

45 The plates 3, 4 of each pair are oppositely disposed and are arranged to have their corrugations extend into each other with the corrugated marginal portions of the plates along their longitudinal edges offset and interfit-

ting to space apart the remaining intermediate portions of the plates to provide the water passage 5 between them, as shown in Fig. 3. In practice, the plates 3, 4 of each pair are integrally joined at one end by making the 60 plates from a single piece of sheet metal ribbon stock and folding it on itself intermediate its ends after being corrugated to bring the plates into the relation shown.

The several pairs of plates 3, 4 are spaced 65 apart to provide the air passages 6, 6 by corrugated strips 7, 7 between and along the longitudinal edges of these plates, as shown. The corrugations of these strips 7 conform to the shape of the corrugations of the plates 3, 4 70 and, when made on hexagonal lines as shown in the drawings, give the front and rear faces of the core a honeycomb appearance. These strips 7 are integrally connected with their respective plates 3, 4 at spaced intervals in the 75 length thereof, and are folded over on the plates in the making thereof as in the Erickson Patent No. 1,233,765, granted July 17, 1917.

80 A vertically disposed flat sheet metal spacer or division plate 8, made in accordance with my invention, is placed in each air passage 6 between the plates 3, 4 forming the same. This plate 8 is narrower than the depth of the core and lies between the strips 7, 7, the latter holding the plate 8 from displacement 85 from front to rear of the core, as shown in Fig. 3.

Each plate 8 is provided with a plurality of truss-like projections 9, 9 preferably arranged 90 in rows lengthwise of the plate and on the safe side thereof, as shown in Fig. 4. Said projections 9, 9 are preferably formed by shearing the plate 8 along the lengths of the projections at the opposite sides thereof and then pressing the same out of the body of the plate to one side and shaping the projections to have flat mid-portions 10, 10 and inclined end portions 11, 11.

95 The plate 8 is placed in the air passage between its associated plates 3, 4 with the projections 9, 9 extending into the corrugations of plate 4 on the side of the projections and with the inclined end portions 11, 11 of the projections in surface contact with the inclined side walls of the said corrugations, as shown in Figs. 2 and 5. Thus in assembling 100 the core, the projections 9, 9 readily find their way into the corrugations of the associated plates 4 and act to center the plates 8 in 105 110

proper relation with their associated plates 3, 4.

As shown in Figs. 2 and 5, the basic dimensions of the projections 9 lengthwise of the flat spacer plate 8 are greater than the width of the entrances of the spaces between the corrugations into which the projections extend. This causes the projections 9 to extend only part way into said spaces and have contact with the inclined portions of the spaces for holding the opposite side of the plate 8 against the crowns of the corrugations of the plate 3. Here the plate 3 has the crowns of its corrugations flattened, as at 12 in Fig. 5, so that relatively wide contact may be had between these plates for increased heat transference from plate 3 to plate 8. This is further enhanced by having the plate 8 in contact with the plate 3 for almost the entire depth of the core, as shown.

The projections 9, 9 are vertically disposed and are arranged edgewise to the general direction of the air currents passing through the core, so as to split the currents and increase air turbulence for turning the colder portions of the air against the heated metal to effect better cooling. In making the projections, openings 13, 13 are formed in the plate 8 at the projections so that the air may pass through the plate from one side to the other to create cross-currents for contact with the heated metal and further increase the turbulence of the air in its passage through the core. The inclined end portions 11, 11 also serve to deflect the air through these openings and against the opposed plates 3 for cooling purposes.

The plate 8 is also provided with a plurality of outwardly projecting wings 14, 14 struck out from the plate on opposite sides thereof, as shown. These wings are disposed at substantially right-angles to the plate 8 with their bases where joined to the plate transverse thereto. Said wings 14 are arranged in rows extending lengthwise of the plate with a plurality of said rows between the two rows of projections 9, 9 and with the wings of both rows extending outward from the same side of the plate. There is a single row of wings 14 between each side or longitudinal edge of the plate and the next adjacent row of projections 9, 9, said wings extending outward from the plate on the same side as the middle rows. The wings of these four rows are also in rows extending across the plate. There is a row of said wings in line with the projections 9, 9 and alternating therewith, as shown. The last named wings of one row are in staggered relation with respect to the wings of the other row, and this disposes the wings of one row laterally opposite the opposed projections 9, 9 to further increase the air turbulence.

The wings 14 provide openings 15 in the plate 8 opposite the wings for cross-currents,

and the wings on the side of the plate 8 opposite the projections 9, 9 extend into the adjacent corrugations of the plate 3 and engage against the plate 3 in its corrugations, as shown. In its corrugations, the plate 3 has outwardly bulged portions 16, 16 and 17, the latter being larger than the first two and on opposite sides thereof, as shown in Fig. 6, to interrupt the air passing through the core to increase air turbulence to further aid in turning the colder air against the heated metal. The wings and projections present increased metal surface to the air currents for carrying off heat from the core.

The details of structure shown and described may be variously changed and modified without departing from the spirit and scope of my invention. After being assembled, solder is applied to the front and rear surfaces of the core along the edges of the corrugated plates and strips, by dipping or otherwise, to close the joints along the water passages and to also connect the parts together.

I claim as my invention:

1. In a radiator core, the combination with two spaced apart corrugated plates, of a flat spacer plate between the corrugated plates and having a plurality of truss-like projections struck out therefrom all on one side of said spacer plate, said projections extending into the corrugations of one of said corrugated plates and engaging the inclined portions thereof for holding the spacer plate against the other corrugated plate, the latter having the crowns of its corrugations flattened to increase the area of contact with the spacer plate.

2. In a radiator core, the combination with two corrugated plates, having narrow corrugated strips at and between the longitudinal edges of said plates for spacing the same apart, a flat spacer plate between the corrugated plates and having a plurality of truss-like projections struck out therefrom and extending into the corrugations of one of said corrugated plates and in contact therewith for holding the flat body portion of the spacer plate against the other corrugated plate, said spacer plate having its side edges at said strips and in contact with said last named plate between said strips.

3. In a radiator core, the combination with two spaced apart corrugated plates, of a flat spacer plate between the corrugated plates and having a plurality of truss-like projections struck out therefrom and extending into the corrugations of one of said corrugated plates and in contact therewith for holding the spacer plate against the other corrugated plate, said spacer plate being provided with a plurality of wings struck out therefrom and extending into the corrugations of the last named plate, said plate having outwardly extending portions at the

bases of its corrugations for contact with said wings and with bulged out portions on opposite sides thereof.

4. In a radiator core, the combination with two spaced apart zigzag corrugated water passage plates, of a flat spacer plate between the corrugated plates and having a multiplicity of truss-like projections struck out from one side of said spacer plate and extending into the spaces between the corrugations of one of said corrugated plates, said projections having their basic dimensions lengthwise of the spacer plate greater than the width of the entrances of said spaces so that the projections extend only part way into said spaces and contact with the inclined portions thereof for holding the flat body of the spacer plate on the side opposite said projections against the crowns of the corrugations of the other corrugated plate and with the portions at the outer ends of the projections bridging across the spaces into which the projections extend.
5. In a radiator core, the combination with two spaced apart zigzag corrugated water passage plates, of a flat spacer plate between the corrugated plates and having a multiplicity of truss-like projections struck out from one side of said spacer plate and extending into the spaces between the corrugations of one of said corrugated plates, said projections having their basic dimensions lengthwise of the spacer plate greater than the width of the entrances of said spaces so that the projections extend only part way into said spaces and contact with the inclined portions thereof for holding the flat body of the spacer plate on the side opposite the projections against the crowns of the corrugations of the other corrugated plate and with the portions at the outer ends of the projections bridging the spaces into which the projections extend, said spacer plate also being provided with a multiplicity of outwardly projecting wings struck out therefrom and distributed thereover and extending into the spaces between the corrugations of the corrugated plates.
6. In a radiator core, the combination with two spaced apart zigzag corrugated water passage plates, of a flat spacer plate between the corrugated plates and having a multiplicity of truss-like projections struck out from one side of said spacer plate and extending into the spaces between the corrugations of one of said corrugated plates, said projections having their basic dimensions lengthwise of the spacer plate greater than the width of the entrances of said spaces so that the projections extend only part way into said spaces and contact with the inclined portions thereof for holding the flat body of the spacer plate on the side opposite the projections against the crowns of the corrugations of the other corrugated plate and with the portions at the outer ends of the projections bridging the spaces into which the projections extend, said spacer plate also being provided with a multiplicity of wings struck out therefrom on opposite sides thereof and distributed thereover and extending into the spaces between the corrugations of both of said corrugated plates, the wings on one side of the spacer plate engaging the corrugated plate toward which said wings extend, while the wings on the opposite side of the spacer plate terminate short of the other corrugated plate toward which said wings extend.

In testimony whereof I affix my signature this 3rd day of June, 1925.

JOSEPH D. HARRIS.
